VENTILATING DEVICE FOR SEWING MACHINES

Israel Bien, San Francisco, Calif.

Application March 29, 1943, Serial No. 480,976

3 Claims. (Cl. 230—248)

This invention relates to a new and improved ventilating device for use in connection with sewing machines.

An object of the present invention is to provide a ventilating device that is especially constructed to be positioned onto the bed of a sewing machine and directly connected to the drive shaft thereof and to thus cause the ventilating fan to be revolved in synchronism with the operation of the sewing machine, thereby producing a cooling effect on the bearing of the machine and also providing proper ventilation for the operator.

Another object of the present invention is to provide novel means for adjusting the longitudinal center of the ventilating fan's drive shaft whereby the device can be operatively connected to various types of sewing machines having different heights and readily disconnected from the same.

Another object of the invention is to provide a meter operated by the fan shaft to record the number of stitches the sewing machine makes, by recording the revolutions of the fan shaft which is in direct driving relation to the sewing machine shaft.

Other objects and advantages will appear in the course of the following description.

In the accompanying drawing forming part of the specification and in which like numerals are employed to designate like parts throughout the same:

Fig. 1 is a front elevational view of the improved sewing machine ventilating device.

Fig. 2 is a central vertical longitudinal sectional view taken on line 2—2 of Fig. 1, looking in direction of the arrows, and Fig. 3 is a reduced side elevational view of the device and also shows the head portion of a sewing machine in dot and dash outline illustrating how the ventilating fan shaft is positioned in alignment with the sewing machine's drive shaft and directly connected thereto.

Referring in detail to the different parts, the numeral 5 designates a cylindrical casing that is preferably constructed with a pair of cross-bars 6 forming a central bearing support as at 7 and is provided with a removable wire guard 8 as shown in Figs. 1 and 2. A suitable ventilating fan 9 is positioned within the casing and is secured to the drive shaft 10 as by pin 12 or otherwise, said shaft being journaled into a suitable bearing 13 that is driven into the bearing support 7. The numeral 13' designates an oil hole for enabling the bearing to be lubricated.

A collar 14 is mounted onto the outer end portion of the shaft 10 and is fixed thereto by a pin 11.

The casing 5 is fixed at its lower edge onto the upper end of a pipe column 15 by preferably being welded thereto as at 16, the lower end portion of the pipe being externally threaded as at 17 to engage into a flanged foot 18 that is internally threaded as at 19, a set screw 20 serving to lock the two members together. A plurality of holes 21 are provided through the flanged portion of the foot to facilitate fastening the device to the bed or table 22 of the sewing machine by suitable screws 23.

15 The inner end portion of the shaft 10 is flattened similar to a screw driver as at 24, so that it will fit into the kerf or slot 25 of a screw 25' provided at the outermost end of the sewing machine's drive shaft 26, adjacent the drive 20 pulley 29 thus directly connecting the two shafts together. When it is desired to disconnect the shafts the sewing machine is stopped with the kerf of its screw extending horizontally, the set screw 20 is loosened and the casing 5 carrying the shaft 10 is swung on a horizontal plane to remove the flattened end of the shaft 24 from the kerf 25. The fan shaft can also be adjusted into true alignment with the sewing machine's drive shaft by simply adjusting the foot member 18 before securing to the table 22. Also it may be raised or lowered somewhat by screwing or unscrewing the pipe 15 in the foot.

In Fig. 3 there is illustrated the preferred position of the ventilator with respect to the sewing machine. The numeral 25' designates the pulley retaining screw at the end of the drive shaft of the machine that extends through the head 27 and operates the needle bar 28. The numeral 29 designates the driving pulley that carries the conventional drive belt 30. In various types of sewing machines this pulley is fixed to the drive shaft by a screw as at 25' that extends into the end of the shaft, the head of the screw being tightened against the pulley.

45 Though in rare cases where the slotted screw may not exist, the slot 25 can easily be provided directly into the end of the drive shaft, or, the connection of Fig. 4 may be used, as will now be described.

50 Fig. 4 shows a modified form of detachably connecting the fan shaft 10 to the sewing machine, and consists of providing a collar 38 slidably fitted to shaft 10 and provided with a set screw 39 for holding it in adjusted position. A 55 soft rubber extension 40 is cemented or other-

wise secured to the collar and is cup shaped on the outer end as at 41 to engage over the screw 25' or shaft terminal, and preferably to snugly contact the pulley 29, and so held by tightening the set screw 39. This modification may also be used in exceptional cases where there may be no slotted screw at the end of the drive shaft.

Due to the high rotating speed of the drive shaft in the average modern sewing machine the said drive shaft and the bearing thereof, that is positioned within the head 27, often became extremely hot causing excessive wear. The average conventional sewing machine drive pulley 29 is constructed with a plurality of holes that extend through the sides thereof and air from the 10 ventilating fan traveling in direction of the arrows 31 will be forced directly onto the bearing that is provided into the head 27, serving to cool the same and a portion of the same air coming from the fan will be diverted toward the operator of the machine, thus also providing an efficient method for producing proper ventilation in hot weather.

Means for recording the number of stitches made by the sewing machine, which is also the 15 number of revolutions the fan makes, is shown as comprising a bracket 22 extending from the end portion of the shaft bearing body 13 and carrying a conventional revolution recording meter 33 secured to the bracket by screws 34.

The outer end portion of the meter's shaft 35 is preferably flattened as at 36, and engages into a slot 37 provided into the outermost end of the fan shaft's collar 34, thus keying the meter to the fan shaft in a manner similar to the construction employed for keying the fan shaft to the sewing machine's shaft.

It is to be understood that the form of my 20 invention herewith shown and described is to be taken as a preferred example of the same and that various changes relative to the material, size, shape and arrangement of parts may be 25

resorted to without departing from the spirit of the invention or the scope of the subjoined claims.

Having thus described my invention, I claim:

5 1. A ventilator for use in combination with a sewing machine, comprising a pedestal, a ventilating fan revolvably supported thereon, said fan having a shaft with a flattened end for facilitating connection to the drive shaft of the sewing machine, and adjustable means for varying the height of the pedestal for facilitating alignment of said shafts.

10 2. A ventilator for use in combination with a sewing machine and adapted to be operated by the drive shaft thereof, said ventilator comprising a pedestal embodying in its construction a vertically disposed pipe column, a casing in the form of a cylindrical shell fixed onto the upper end of said pipe column, a ventilating fan member including a shaft revolvably supported in said casing, the fan shaft extending through said casing and having a flattened end adapted to project into the conventional transversely extending slot in the screw at the end of the sewing machine's drive shaft, and a foot member adjustably secured to the lower end portion of the pedestal whereby the height of the pedestal can be varied, facilitating the connecting and aligning of said shafts.

15 3. A ventilator for use in combination with a sewing machine, comprising a pedestal, a ventilating fan revolvably supported thereon, said fan having a shaft projecting in alignment with the sewing machine shaft adjacent the belt pulley thereof, the fan being directed toward the sewing machine shaft, and means forming a quick detachable direct connection from the fan shaft to the sewing machine shaft for operating said fan, including means whereby said fan and its shaft may be bodily swung on said pedestal on a vertical axis in disconnecting the shafts.

20 ISRAEL BIEN.
